FUSE HOLDER AND CIRCUIT DISCONNECT
DEVICE

Walter P. Keller, Chicago, Ill.

Application June 22, 1949, Serial No. 100,577

2 Claims. (Cl. 200—128)

1

This invention relates to a greatly improved fuse holder which can also be conveniently employed as a safe and certain circuit disconnect device.

Ever since the general adoption of fuses as circuit protective devices, a great need has existed for a satisfactory fuse holder. Fuse holders heretofore employed have had serious disadvantages, both from the standpoint of convenience and safety.

In fact, the inadequacy of prior-art fuse holders has been in large part responsible for the extensive use of circuit breakers, notwithstanding their much higher cost as compared to thermal fuses.

Most thermal fuses employed in industrial and commercial electrical installations are of the cartridge type. This type of construction is highly desirable from the standpoint of fuse manufacture, since it is inexpensive and well adapted to mass production.

The only fuses in general use which are not of the cartridge type are the screw-base fuses commonly used in home lighting circuits. The screw-base fuse is much more expensive to construct than the cartridge fuse, and it is frequently unsatisfactory in service because, first, circuit failure often results from imperfect contact due to loose insertion and, second, the open receptacle into which the fuse is to be inserted invites accidental shock.

In spite of the shortcomings just described, the screw-base fuse has nevertheless remained in general use for home electrical installations simply because it has been, with all its disadvantages, safer in unskilled hands than the cartridge fuse as employed with any of the prior-art fuse holders.

An important object of my present invention is to provide a fuse holder for cartridge fuses which is entirely safe in use, even when being handled by totally inexperienced persons.

Another object of my present invention is to provide a fuse holder with which fuses can be replaced with complete safety from shock and without the necessity for opening a master line switch. This advantage of my present invention is of great practical importance, since changing a fuse in prior-art practice, whether the fuse be of the cartridge or screw-base type, has always required that the master line switch be open. This has usually resulted in temporary interruption of electric service to a number of circuits other than the one affected by the fuse to be replaced. The inconvenience and lack of

economy in such an arrangement is obvious. It has, as a practical matter, been particularly objectionable in apartment houses, hotels, and office buildings.

5 A further object of my invention is to provide a fuse holder physically removable in its entirety from the electrical circuits with which it is normally associated. This feature yields two important advantages—first, it insures that 10 at the time the fuse is replaced, no possibility of shock can exist, and, second, it permits replacement of the fuse at a place and under conditions of light which are convenient rather than compelling the person replacing the fuse 15 to fumble dangerously about a fuse box in a dark corner of an engine room or an apartment house basement. This feature of my invention represents a great forward step over prior-art cartridge fuse holders. Those in prior 20 use have, for the most part, consisted of open spring clamps mounted within a fuse box. Optimum adjustment of the spring clamps has always been an almost impossible task. If the spring tension be made great enough to insure 25 positive contact with the fuse terminals, then manual removal of the fuse without the use of tools is almost impossible. On the other hand, if the spring tension be adjusted to permit easy manual removal, the contact with the fuse terminals is uncertain and likely to fail after a few weeks' accumulation of dirt and oxide has formed 30 on the spring contacts and the fuse terminals.

Another important object of my invention is to obviate the last-mentioned accumulation of 35 foreign matter, oxide, dirt, etc. on the contact surfaces and the fuse terminals; with my present invention, the fuse is held at all times in firm contact with the holder electrodes and at the same time wholly enclosed for protection against 40 access of foreign matter. Moreover, circulation of air around the fuse terminals and electrodes is effectively prevented, thus inhibiting oxidation almost completely.

Still another object of my invention is to provide 45 a fuse holder having a protective casing which can be disassembled at will, without tools, for the replacement or removal of a fuse and wherein, upon reassembly, positive means are provided to maintain the terminals of the fuse in firm contact with the electrodes of the fuse holder.

A still further object of my invention is to provide 50 a fuse holder having no external electrical conducting surfaces and being physically removable, without tools, from its associated electrical

circuit, thus permitting use of the fuse holder as a convenient circuit disconnect device supplementing or replacing the usual master line switch.

Another object of my invention, corollary to the object last stated, is to provide a fuse holder which can readily be assembled in tandem units or in triple units so as to function as master line fuses and master disconnect device for all conductors of a single-phase or three-phase power line.

Still another object of my invention is to provide a fuse holder for cartridge fuses having no electrical conductors externally accessible by manual contact and yet providing convenient means for testing the continuity of the fuse without physical removal of the fuse holder.

Other objects and advantages of my invention will appear as the specification proceeds.

An illustrative embodiment of my invention is illustrated in the accompanying drawing, of which Figure 1 is a perspective view of a fuse holder made in accordance with my invention; Fig. 2, a view in side elevation of the fuse holder of Fig. 1, the holder being shown mounted within a wall receptacle adapted to receive it; Fig. 3, a top plan view of the fuse holder of Fig. 1 as it appears with the cap removed; Fig. 4, a bottom view of the fuse holder of Fig. 1; Fig. 5, a sectional view of my fuse holder, the section being axial and in a plane perpendicular to the contact prongs; Fig. 5 also shows diagrammatically circuit connections to illustrate the manner of insertion of my fuse holder in an electrical circuit; Fig. 6, a sectional view similar to Fig. 5 but differing therefrom in that the cap, the fuse, and the removable electrode shown in Fig. 5 have been removed; Fig. 7 is a sectional view taken through the base of my fuse holder along the line 7-7 of Fig. 5; and Fig. 8, a sectional view through the body portion of my fuse holder along the line 8-8 of Fig. 5.

As may be seen from the figures, the embodiment of my invention illustrated in the drawing has a body portion 10 of generally tubular shape. The lower end of body 10 merges into an annular shoulder 11, formed integrally with body 10. The upper end of body 10 is provided with threads 12 adapted for co-operation with corresponding internal threads on cap member 13.

The body portion 10, with its lower annular shoulder 11, are made of insulating material and, in the normal case, will be integrally molded from a plastic material such as hard rubber or "Bakelite." Similarly, the cap 13 is formed of insulating material and, like the body member 10, is preferably molded from a plastic material.

As may be best observed from Figs. 5 and 6, body member 10 of my fuse holder is provided with an axial hollow portion 15 of cylindrical shape and of size adapted to receive readily the particular fuse to be carried by the fuse holder. Central opening 15 is open at the upper end of body 10; it extends at its lower end to a point near the bottom of base shoulder 11, but a retaining wall or floor 11a provides a bottom for central opening or fuse socket 15.

A metal contact prong 14 is securely locked within the base shoulder 11, preferably by being molded in at the time body member 10 and base shoulder 11 are originally formed. Contact prong 14 is provided with an orthogonally disposed portion 14a which, as is best shown in Figs. 5, 6, and 7, entirely covers the inner surface of wall 11a and thus provides a contact electrode

for the lower terminal of fuse 16 when it rests within socket 15. A detent 14b may be provided on the shank of prong 14 to assist in securing it in its socket.

In a plane parallel to the plane occupied by the prong portion of member 14, body member 10 is equipped with a slot 17 extending entirely through body member 10 and base shoulder 11. The wall 18 which separates slot 17 from fuse socket 15 is relieved for a short distance at its upper end so as to provide a communicating passage between slot 17 and socket 15 below the top-most extremity of the body member proper. This last-mentioned construction is clearly shown in Figs. 5 and 6.

A metal electrode member 19 comprises a straight shank portion formed and shaped for cooperation with slot 17 and an orthogonally disposed portion 19a. Member 19a should preferably be rounded at its terminal portion, as shown in Fig. 3, to seat readily within fuse socket 15.

As may be seen from Fig. 5, prong member 19, when my fuse holder is assembled for use, is received within slot 17, the length of the shank portion of prong member 19 being such that it extends outward beyond the bottom portion of base shoulder 11 to form a contact prong substantially equal in length to prong 14.

The prongs 14 and 19 are adapted to be plugged into a suitable electrical receptacle; an illustrative receptacle 21 is shown in Fig. 2, mounted within a terminal box or casing 22. It will be understood that the dimensions of prongs 14 and 19 may be varied within wide limits to adapt my fuse holder to a particular type of receptacle or to adapt it for handling currents of various magnitudes. It will be obvious to anyone skilled in the art that an embodiment of my fuse holder adapted to carry, for example, a 100 ampere fuse in heavy duty service would be provided with more massive prong members 19 and 14 than would be appropriate for an embodiment of my fuse holder intended for domestic household service with a 15 or 20 ampere fuse.

A small aperture 23 is provided in cap member 13; the thickness of cap member 13, while not critical, should be sufficiently great to prevent any manual contact with electrode 19a through aperture 23. Aperture 23 is intended to accommodate a test probe for purposes which will be more fully described in a succeeding paragraph hereof.

In the replacement of a fuse in my fuse holder, the operator first grasps my fuse holder by the body 10 and physically withdraws it from the receptacle within which it is carried. This operation entails absolutely no danger of shock, since no manual contact with any conducting material is involved in the removal of my fuse holder from its receptacle.

The cap 13 is then unscrewed from body member 10, and prong member 19 is removed. This last operation may be accomplished merely by holding the fuse holder in a bottom-up position; member 19 will thereupon fall out of slot 17 by force of gravity. Fuse 16 may thereupon be easily removed from fuse socket 15 and replaced with a suitable renewal fuse. After the new fuse 16 is seated within socket 15, as shown in Fig. 5, electrode member 19 is thereupon returned to slot 17 and seated firmly in position with the orthogonally disposed electrode 19a making face-to-face contact with the upper terminal of fuse 16. Cap member 13 is thereupon screwed back into place on body member 10; cap 13 is thus pressed

with a firm and positive force against electrode 19a. This force is in turn transmitted through fuse 16 to electrode 14a. Accordingly, when cap member 13 is screwed securely and tightly onto body member 10, the fuse 16 is held tightly within socket 15, secure against vibration and assured of excellent electrical contact between its respective terminals and electrodes 14a and 19a.

When the just-described operation has been completed, my fuse holder may then be replaced in its receptacle, once again with perfect assurance that no danger or shock exists. It should be noted that the operation involved in replacing a fuse may be accomplished without any necessity whatever for opening a master line switch or otherwise interfering with the electrical circuit which may be supplying a number of lines other than that affected by the fuse being replaced.

It may be noted that the embodiment of my invention shown in the drawing is provided with polarized prongs—that is, the physical width of prong 19 is somewhat less than that of prong 14, so that, given a similarly-formed receptacle, my fuse holder can be inserted in only one position. While the use of polarized prongs and receptacle is a refinement which may be dispensed with if desired, its use does provide one special advantage which may be very convenient. When a polarized receptacle is employed, connections should be made as indicated diagrammatically in Fig. 5. Therein a power line, one side of which is conventionally grounded, is connected through my fuse holder to an electric motor 25. The receptacle connections should be such that prong 14 is connected directly to the power line (on the ungrounded side, of course) while the prong 19 is connected to the motor 25. The other terminal of motor 25 is of course connected to the grounded side of the power line. When the receptacle for my fuse holder is connected as shown in Fig. 5, the aperture 23 may be very conveniently employed, in conjunction with a test probe, to determine whether the fuse within the holder is good or bad. Fuses are normally tested by using a light bulb or other indicating source connected in series between ground and the test probe. If such apparatus is employed with my fuse holder, the test probe may be inserted through aperture 23 and thus brought in contact with electrode 19a. If the fuse is good, the test light will glow; if the fuse is bad, there will be no indication from the test light, since the circuit will be broken between the "hot" side of the line and electrode 19a.

As may be seen from the structural advantages herein described, the normal function of my invention as a fuse holder may be supplemented by the additional function of circuit disconnect device. It will be obvious to those skilled in the art that my invention can readily be formed in tandem or in triplicate units; such construction would merely involve the molding in a single piece of as many body members 10 as might be desired, they being joined one to another by an integral base member 11. Such a double or triple fuse holder unit could be easily designed for co-operation with a double or triple receptacle; such receptacles are well known and in general use. Such a tandem or three-unit fuse holder could thus be readily connected to a single-phase or three-phase power line so as to

5 fuse each leg of the line and, upon removal of the fuse holder, to disconnect each leg of the line. My invention could thus safely and inexpensively replace the complicated and expensive knife switches which are in general use as main line switches today. Moreover, since my invention is inherently shock-proof, the elaborate means customarily employed for protecting the user of such knife switches against shock can be dispensed with entirely.

10 15 20 25 30 35 40 45 50 While I have in this specification described in considerable detail a particular illustrative embodiment of my invention, it is obvious that persons skilled in the art may introduce many variations in details without departing from the spirit of my invention; it is accordingly my desire that the scope of my invention be not limited to the particular embodiment shown and described herein but that such scope be determined solely with reference to the appended claims.

I claim:

1. A fuse holder comprising a cylindrical body member having an axial socket therein for receiving a cartridge fuse and having also a slot 25 adjacent said socket, said socket having a bottom wall and an open end opposite thereto, an electrode member mounted in the end of said body member adjacent said bottom wall, said electrode having a base portion extending across said bottom wall and a shank portion extending externally from the bottom of the body member to form a contact prong, an electrode member for the open end of the socket adapted to make electrical contact with the outer terminal of a cartridge fuse received within the socket, the inner terminal of such fuse being pressed against said bottom wall electrode member, said open-end electrode member having an elongated shank adapted to be removably received in said slot and to extend therefrom externally to the body member when said electrode is seated against the fuse terminal and to form a contact prong, adapted with said first-mentioned contact prong to be plugged into a receptacle, and locking cover means for the body member adapted to close off the open end of the socket and, when in locking position, to clamp the fuse between said open-end electrode and the body member, the external portions of said body member and the locking cover being formed entirely of insulating material.

2. A fuse holder according to claim 1 wherein a small hole is provided in the locking cover to permit access with a test probe to the electrode therebelow while preventing manual access to the electrode so long as the cover is in locking position.
